Watson E. Coleman

Attorney

UNITED STATES PATENT OFFICE.

BENJAMIN F. HIGGINS, OF ST. LOUIS, MISSOURI.

DOOR-LOCK.

1,200,942.

Specification of Letters Patent. Patented Oct. 10, 1916.

Application filed July 22, 1916. Serial No. 110,713.

To all whom it may concern:

Be it known that I, BENJAMIN F. HIGGINS, a citizen of the United States, residing at St. Louis and State of Missouri, have invented certain new and useful Improvements in Door-Locks, of which the following is a specification, reference being had to the accompanying drawings.

This invention relates to certain improvements in door locks and it is an object of the invention to provide a device of this general character having novel and improved means wherein the latch is retracted upon axial rotation being imparted to a spindle.

It is also an object of the invention to provide a lock of this general character having novel and improved means wherein one of the knobs coacting with the spindle is capable of movement independently of the spindle, and whereby said knob and spindle may be locked in order to cause the same to rotate in unison to effect retraction of the latch.

Furthermore it is an object of the invention to provide a novel and improved latch of this general character wherein the independently rotatable knob may be locked to the spindle by a key disposed through the knob and coacting with the spindle, and whereby said knob may be locked to the spindle from the opposite side of the door through the medium of an endwise movable member.

The invention consists in the details of construction and in the combination and arrangement of the several parts of my improved door lock whereby certain important advantages are attained and the device is rendered simpler, less expensive and otherwise more convenient and advantageous for use, all as will be hereinafter more fully set forth.

The novel features of the invention will hereinafter be definitely claimed.

In order that my invention may be the better understood, I will now proceed to describe the same with reference to the accompanying drawings, wherein—

Figure 1 is a view partly in section and partly in top plan illustrating a door lock constructed in accordance with an embodiment of my invention, a coacting portion of the door being also indicated in section; Fig. 2 is a fragmentary vertical sectional

view taken through the device as illustrated in Fig. 1; Fig. 3 is a sectional view taken substantially on the line 3—3 of Fig. 1; looking in the direction of the arrow; Fig. 4 is a view in elevation of the inside knob with the retaining flange omitted, as herein embodied; Fig. 5 is a view in perspective detached of the yoke member, herein included; and Fig. 6 is a view in plan of a key adapted to be employed in connection with my improved door lock.

As disclosed in the accompanying drawings, 1 denotes a portion of a door having produced in the edge thereof a recess 2 to receive therein the casing 3 of the latch 4 normally maintained in a projected adjustment through the medium of the expandable member 5, herein disclosed as a conventional coil spring, surrounding the latch intermediate the head 6 thereof and the turned flanges 7 arranged at the inner end of the casing 3. The inner end portion of the latch 4 is provided with a tubular extension 8 to the outer extremity of which is clamped the yoke member 9 through the medium of the headed threaded member 10, disposed through the base plate 11 of the yoke member 9 operatively engaged within the bore of the tubular extension 8.

As herein disclosed, the upper and lower arms 12 of the yoke member 9 are substantially V-shape in form with their apexes disposed outwardly whereby said yoke is triangular in plan, and disposed within the recesses afforded by the arms 12 are the oppositely directed fingers 14 carried by the spindle 15 disposed transversely of the door 1 through a suitable opening 16 and with which communicates the recess 2 hereinbefore referred to. By this arrangement it will be perceived that upon axial rotation being imparted to the spindle 15, the latch 4 will be retracted and that said latch will assume an extended or normal position under the influence of the expandable member 5.

It will also be at once noted that the formation of the arms 12 permit an inward or retracted movement of the latch 4 independently of the movement of the spindle 15 when the latch 4 or more particularly the head 6 thereof, is forced inwardly upon the shutting of the door.

The spindle 15 extends beyond opposite sides of the door 1 and coacting with the projecting portion of the spindle at the in-

side of the door is the knob 17, the tubular shank 18 of which receiving said spindle and having a key-way 20 registering with the key-way 19 disposed longitudinally of the spindle throughout substantially its entire length and in which the endwise movable key or member 21 is mounted, the outer end of said member or key being angularly disposed, as at 22, so that the same may be 5 engaged within the parallel slots 23 intersecting the key-way or slot formed in the shank 18, whereby said key or member may be locked in different positions longitudinally of the spindle 15 for a purpose to be hereinafter more particularly referred to. The inner end of the shank 18 is also provided with the outwardly disposed annular flange 24 with which the annular plate or disk 25 fixed to the door 1 coacts in order 10 to maintain the knob 17 together with the shank 18, in applied position.

The portion of the spindle 15 which extends beyond the outer side of the door 1 is disposed within the tubular shank 26 of the knob 27, the inner end of the shank having 15 in threaded engagement therewith the annular member 28, underlying the annular disk or plate 29 affixed to the outer face of the door, whereby said shank 26 and knob 27 are rotatably supported. Normally the knob 27 and shank 26 are freely rotatable upon the spindle 15 and when the door is closed and it is desired to retract the latch 4 from the outside, a key K is inserted within 20 the bore of the shank 26 through a suitable key slot 30 formed preferably at the axial center of the knob 27, and as herein embodied, said key K has its inner end provided with the extensions or fingers 31 adapted to be received within the recesses or 25 openings 32 formed in the outer end of the spindle 15, whereby it will be perceived that the spindle 15 and knob 27 will be caused to rotate in unison. It is also to be noted that the inner end of the bore of the shank 26 is provided with a key-way 33 in register 30 with the key-way 19 in the spindle 15, so that the key or endwise movable member 21 may be moved into operative engagement with the shank 26, whereby said shank is locked to the spindle. This latter arrangement is for a purpose which is believed to be self-evident.

It is to be noted that the inner extremities of the fingers 14 are integrally connected by the loop 34 which straddles the spindle 15 and bridges the key-way 19 within the spindle and thereby affording a guide for the key or endwise movable member 21. It 55 is to be further noted that the intermediate loop 34 is fixed to the spindle 15 through the medium of the rivet 35 disposed through said loop and spindle.

It is preferred that the key or endwise 60 movable member 21 be circular in cross sec-

tion, and it will be readily understood from the accompanying drawings that when said key or member has been adjusted into engagement with the shank 26, that the angular extremity 22 of the key will be engaged within the inner parallel slot 23 to hold said member in this adjustment. It will also be understood that when the member or key 21 is adjusted out of engagement with the shank 26, that the angular extremity 22 thereof is engaged within the outer slot 23.

From the foregoing description, it is thought to be obvious that a door lock constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

1. A door lock comprising a latch mounted for reciprocatory movement, a spindle coacting with the latch for imparting movement thereto in one direction, a knob mounted upon one end of the spindle, an endwise movable key coacting with the spindle and the knob for securing the knob to the spindle, a second knob loosely engaged with the opposite end of the spindle and provided with a key-way adapted to be engaged with the hereinbefore-mentioned key upon movement thereof in one direction for locking the second knob to the spindle.

2. A door lock comprising a latch mounted for reciprocatory movement, a spindle coacting with the latch for imparting movement thereto in one direction, a knob mounted upon one end of the spindle, an endwise movable key coacting with the spindle and the knob for securing the knob to the spindle, a second knob loosely engaged with the opposite end of the spindle and provided with a key-way adapted to be engaged with the hereinbefore-mentioned key upon movement thereof in one direction for locking the second knob to the spindle, and a member insertible through the second named knob and coacting with the adjacent end of the spindle for locking said knob and spindle together.

3. A door lock comprising a latch mounted for reciprocatory movement, a spindle coacting with the latch for imparting movement thereto in one direction, a knob mounted upon one end of the spindle, an endwise movable key coacting with the

spindle and the knob for securing the knob to the spindle, a second knob loosely engaged with the opposite end of the spindle and provided with a key-way adapted to be engaged with the hereinbefore-mentioned key upon movement thereof in one direction for locking the second knob to the spindle, said key and first mentioned knob being provided with coacting means whereby said key may be locked into or out of engagement with the second named knob.

In testimony whereof I hereunto affix my signature in the presence of two witnesses.

BENJAMIN F. HIGGINS.
